UNITED STATES PATENT OFFICE

151,987

DESIGN FOR A WATER HEATER

Jon W. Hauser, Oak Park, Ill., assignor to Sears, Roebuck and Co., Chicago, Ill., a corporation of New York

Application March 8, 1947, Serial No. 137,460

Term of patent 14 years

(Cl. D81—2)

To all whom it may concern:

Be it known that I, Jon H. Hauser, a citizen of the United States of America and a resident of Oak Park, county of Cook, and State of Illinois, have invented a new, original, and ornamental Design for a Water Heater, of which the following is a specification, reference being had to the accompanying drawing, forming a part thereof.

The figure is a perspective view of a water heater embodying my new design.

The back of the device not shown in the drawing is substantially plain.

I claim:

The ornamental design for a water heater, substantially as shown and described.

JON W. HAUSER.
